UNITED STATES PATENT OFFICE.

JAMES RADLEY, OF BROOKLYN, NEW YORK.

DESIGN FOR LOCOMOTIVE HEAD-LIGHTS.

Specification forming part of Design No. **7,523**, dated June 30, 1874; application filed June 6, 1874.
[Term of Patent 14 years.]

To all whom it may concern:

Be it known that I, JAMES RADLEY, of the city of Brooklyn, in the county of Kings and State of New York, have invented a Design for Locomotive Head-Lights, of which the following is a specification:

The nature of my design is fully represented in the accompanying drawing, to which reference is made.

My head-light is made oval in form. A represents the body portion or case of the head-light; B, the reflector; C, the burner; D, the

cap; E, the base. The small dots at the base represent openings for the admission of air.

I have on file in the Patent Office an application for the mechanical features shown in this design.

What I claim as my invention is—

The design for an oval-shaped head-light for a locomotive, substantially as set forth.

JAS. RADLEY.
